[57] CLAIM

The ornamental design for the recycling bin, as shown and described.

DESCRIPTION

FIG. 1 is a perspective view of the recycling bin showing our new design;

FIG. 2 is a side elevational view of the left side of the new recycling bin;

FIG. 3 is a plan view of the new recycling bin;

FIG. 4 is a view of the bottom of the new recycling bin;

FIG. 5 is an elevational view of the front of the new recycling bin; and,

FIG. 6 is a elevational view of the rear side of the new recycling bin; and,

FIG. 7 is a side elevational view of the right side of the new recycling bin.

The broken line showing is for illustrative purposes only and forms no part of the claimed design.
